UNITED STATES PATENT OFFICE.

LAWRENCE J. KELLY, OF EAST PALESTINE, OHIO, ASSIGNOR TO THE McGRAW TIRE & RUBBER COMPANY, OF EAST PALESTINE, OHIO, A CORPORATION OF OHIO.

DESIGN FOR A RUBBER TIRE.

53,129.

Specification for Design.

Patented Mar. 25, 1919.

Application filed November 20, 1918. Serial No. 263,430. Term of patent 14 years.

To all whom it may concern:

Be it known that I, LAWRENCE J. KELLY, a citizen of the United States, residing at East Palestine, in the county of Columbiana, in the State of Ohio, have invented a new, original, and ornamental Design for Rubber Tires, of which the following is a specification, reference being had to the accompanying drawing, forming a part thereof.

Figure 1 is a plan view of a segment of a tire showing my design applied to the tread of the tire; Fig. 2 is a section on line 2—2 of Fig. 1.

I claim:

The ornamental design for a rubber tire as shown.

In testimony whereof I affix my signature.

LAWRENCE J. KELLY.
